(57) **CLAIM**

The ornamental design for a portable charger, as shown and described.

DESCRIPTION

FIG. 1 is a front side top perspective view of our new design for a portable charger;

FIG. 2 is a back side bottom perspective view of FIG. 1;

FIG. 3 is a left end view of FIG. 1;

FIG. 4 is a right end view of FIG. 1;

FIG. 5 is a front elevational view of FIG. 1;

FIG. 6 is a back elevational view of FIG. 1;

FIG. 7 is a top view of FIG. 1; and,

FIG. 8 is a bottom side view of FIG. 1.

The broken lines illustrate environmental structure and form no part of the claimed design.
